(57) **CLAIM**

The ornamental design for a shoe, as shown and described.

DESCRIPTION

FIG. 1 is a rear, left top perspective view of a shoe showing our new design;

FIG. 2 is a rear, right, top perspective view thereof;

FIG. 3 is a left side view thereof;

FIG. 4 is a right side view thereof;

FIG. 5 is a top view thereof;

FIG. 6 is a bottom view thereof;

FIG. 7 is a rear view thereof; and,

FIG. 8 is a front view thereof.

In the drawings, the dash-dash broken lines show portions of the shoe that form no part of the claimed design.

1 Claim, 4 Drawing Sheets
